UNITED STATES PATENT OFFICE.

GEORGE CHASE EDWARDS, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

ADVERTISING DEVICE.

1,149,347.

Specification of Letters Patent. Patented Aug. 10, 1915.

Application filed September 8, 1914. Serial No. 860,683.

To all whom it may concern:

Be it known that I, GEORGE CHASE EDWARDS, a citizen of the United States, residing at Bridgeport, county of Fairfield, 5 State of Connecticut, have invented an Improvement in Advertising Devices, of which the following is a specification.

This invention has for its object to provide an advertising device comprising a 10 sheet, card or folder and a series of interchangeable parts, which will give any predetermined information that may be desired, as for example the catalogue number, list price, &c., regarding any combination of 15 members that is likely to be called for by the trade.

With this and other objects in view I have devised the novel interchangeable advertising device which I will now describe, 20 referring to the accompanying drawing forming a part of this specification and using reference characters to indicate the several parts.

Figure 1 is a view of my novel advertising 25 device in the form of a two-leaf folder partly broken away to show the backing; Figs. 2 and 3 are views of reverse sides of one of the interchangeable parts detached, and Fig. 4 is a view on an enlarged scale 30 illustrating the operation of the device.

10 denotes a main sheet, card or folder which may be made of any suitable material, as metal, celluloid or paper and is provided with a plurality of slits 11 and with co- 35 operating slots 12. The slots are placed at right angles to the slits. In the present instance the slits are shown as placed transversely of the main sheet and the slots as placed in vertical alinement a short distance 40 below the coöperating slits. Contiguous to each slit, in the present instance immediately below it, I place a representation, indicated by 13, of a member of a combination, as for example a representation of a cap of 45 an electric socket. Contiguous to the slots and on opposite sides thereof, I place indicating symbols 14 arranged in vertical columns, the symbols in the columns being accurately placed to give such predetermined information as may be required regarding any combination of members, as for 50 example the catalogue number of regular goods, the catalogue number of electrolier goods, the number in a standard package

and the list price of the special combination 55 of members.

15 denotes the interchangeable parts, each comprising a card 16 which may be of ornamental configuration, and an attaching tab 17 adapted to be passed into any one of the 60 slits. In order to reduce the number of parts in the device as a whole, the interchangeable parts are made reversible, each side being provided with a representation 18 of a member of a combination and the 65 tab being provided with a transverse indicating mark 19 which, when the tab is inserted in one of the slits with the lower end of the card registering with the slit, will be in horizontal alinement with certain of the 70 indicating symbols 14, as clearly shown in Fig. 4. The reverse side of the tab is provided with a differently placed indicating mark and the reverse side of the card is provided with a representation of another 75 member of a combination.

For convenience in operation, so that it is not necessary to remove an interchangeable part to see what member is represented on the opposite side thereof, I place above 80 the representation 18 of a member a reduced representation 20 of the combination member on the opposite side thereof, for example in Fig. 2 the combination member 18 is an ordinary pull socket and above that is 85 placed a reduced representation of a ceiling pull. Upon the reverse side (see Fig. 3) the combination member is a ceiling pull and above it is placed a reduced representation of an ordinary pull socket. The same 90 principle is carried out in Fig. 4, in which upon the exposed side of the card of the interchangeable part, the combination member is a pendant and on the reverse side a key socket. 95

The operation is as follows: Suppose for example that information is desired regarding the combination of a pendant with the special combination member 13, represented in the column at the right in Fig. 4. The 100 required interchangeable part 15 is selected, the side bearing the representation of a pendant placed outward and the tab of said interchangeable part is then inserted in the slit corresponding with the required combination member 13, as in Fig. 4, the lower end of the card of the interchangeable part being in alinement with the slit and the 105

upper end of the tab substantially filling the slit so that the card is firmly supported. The indicating mark 19 on the tab will now be exposed in the slot in alinement with the 5 indicating symbols 14 giving the desired information. In the present instance it is an electrolier fixture, the catalogue number of the combination is 607, the number in a standard package is 50, and the list price is 10 sixty-six cents.

I preferably provide the main sheet whether in the form of a card or folder with a backing 21 secured at the edges only, so that the tabs when inserted will lie between 15 the main sheet and the backing and the interchangeable parts may be securely retained in place.

Having thus described my invention I claim:

20 1. A device of the character described, comprising a main sheet having transverse slits and vertical slots, representations of combination members contiguous to the slits, and indicating symbols in horizontal alinement contiguous to the slots, and interchangeable parts each comprising a card bearing the representation of a combination member and a tab adapted to be passed into 25 one of the slits and provided with an indicating mark visible through the corresponding slot and adapted to aline with the indicating symbols relating to the combination of members.

30 2. A device of the character described comprising a main sheet having transverse slits and below said slits vertical slots, representations of combination members below the slits and indicating symbols contiguous to the slots, and reversible interchangeable 35 parts each comprising a card bearing on each side the representation of a combination member and a tab adapted to be passed into one of the slits and provided on each side with an indicating mark adapted to be 40 seen through the slot and to aline with the indicating symbols relating to the combination of members.

45 3. A device of the character described comprising a main sheet having transverse slits in vertical alinement and alined vertical slots coöperating therewith, representations of combination members contiguous to the slits and indicating symbols contiguous to the slots and relating to the combination 50 of members, and interchangeable parts each comprising a card bearing the representation of a combination member and a tapering tab adapted to enter any of the slits and provided with an indicating mark adapted to coöperate with the symbols.

4. A device of the character described comprising a main sheet having slits and slots at right angles to the slits, representations of combination members contiguous to the slits and indicating symbols contiguous to the slots and relating to the combination of members, and interchangeable parts each comprising a card bearing the representation of a combination member and a tab adapted to enter any of the slits and provided with an indicating mark adapted to coöperate with the symbols. 65

5. A device of the character described comprising a main sheet having slits and slots at right angles to the slits, representations of combination members contiguous to the slits, and indicating symbols contiguous to the slots, interchangeable parts each comprising a card bearing the representation of a combination member, and a tab adapted to 70 enter any of the slits and provided with an indicating mark adapted to coöperate with the symbols and a backing secured to the main card at the edges thereof, and covering the tabs when inserted in the slits. 75

6. A device of the character described comprising a main sheet having slits and slots at right angles to the slits, representations of combination members contiguous to the slits and indicating symbols contiguous to the slots and relating to the combination of members, and reversible interchangeable 80 parts each comprising a card bearing on each side the representation of a combination member and a reduced representation 85 of the member on the opposite side and a tab adapted to enter any of the slits and provided on each side with an indicating mark adapted to coöperate with the symbols. 90

7. A device of the character described comprising a main sheet having transverse slits and vertical slots, representations of combination members contiguous to the slits and indicating symbols in horizontal alinement contiguous to the slots, interchangeable parts each comprising a card bearing on opposite sides representations of combination members and a tab adapted to be passed into any of the slits and provided on opposite sides with an indicating mark adapted 100 to be seen through the slots and coöperating 105 with the symbols and a backing secured to the main card at the edges and covering the tabs when inserted.

In testimony whereof I affix my signature 110 in presence of two witnesses.

G. CHASE EDWARDS.
